(57) **CLAIM**

The ornamental design for a shock absorber cane, as shown and described.

DESCRIPTION

FIG. 1 is a front view of the shock absorber cane showing a top portion with a curved handle, a telescopic connection, a lower portion, and a spring cushioned ground tip;

FIG. 2 is a right side view of FIG. 1;

FIG. 3 is a left side view of FIG. 1;

FIG. 4 is a bottom view of FIG. 1;

FIG. 5 is a top view of FIG. 1;

FIG. 6 is an enlarged view of the lower portion of the shock absorber cane; and,

FIG. 7 is an isometric view showing an embodied usage configuration of the shock absorber cane.

The broken lines shown in FIG. 7 are for purposes of illustrating environmental structure associated with the claimed design in condition of use, and which forms no part of the claimed design.
